UNITED STATES PATENT OFFICE.

FRANK HERBECK, OF ORANGE, MASSACHUSETTS.

FLOOR-PLANER.

SPECIFICATION forming part of Letters Patent No. 744,757, dated November 24, 1903.

Application filed June 10, 1903. Serial No. 160,942. (No model.)

To all whom it may concern:

Be it known that I, FRANK HERBECK, a subject of the Emperor of Austria-Hungary, residing at Orange, county of Franklin, Commonwealth of Massachusetts, have invented new and useful Improvements in Floor-Planers, of which the following is a specification.

This invention relates to floor-planing machines, and particularly to that class in which a rotary head is used to carry cutters, scrapers, or polishers.

The great difficulty in successfully planing floors with most machines arises from their inability to adapt themselves to the surface conditions of the floors in which boards have become sprung or warped or where the floor has settled in parts.

It is the object of the present invention, therefore, to provide a machine which will follow the general irregularities of the floor while smoothing the surface roughness and which will provide various other new and useful features hereinafter mentioned.

In the drawings, in which like letters of reference indicate corresponding parts throughout, Figure 1 is a side view of the machine; Fig. 2 is a plan; Fig. 3, a longitudinal section; Fig. 4, a top view of the lower sandpaper-block; Fig. 5, a view of the block partially assembled; Fig. 6, a view of the scraper, and Fig. 7 a view of a plane member. Fig. 8 is a detail view of the slit clamp, showing the conical neck S'.

A is a frame mounted upon the axle B of the wheels C, which positively turn the same by pawl-and-ratchet connections when the machine is rolled forward by a handle D, which is removably connected at b. The axle B carries a beveled gear E, which meshes with a gear F on the rear end of the shaft G, which is in turn geared at its forward end to the rotary head H by gears I and J. This head H and its gear J are carried in a bracket K on the frame and are free to rotate therein.

L is a collar fast on the head H, and to it are pivoted arms M, which carry pivoted to their outer ends the tools, the same being pressed into working engagement with the floor by the spring N, adjustable through the screws n.

P is a segmental plane having a slot p in

its side through which the arms M work. This plane is flat throughout most of its length; but its face rises slightly at its forward end to ride over irregularities in the floor.

S is a scraper-blade held in a forked clamp S', which is slit and slightly conical at its neck s, so that it is compressed as it is drawn through the opening in the block S².

S² is a slot in which the arms M are pivoted by the bolt end s' of the clamp S'. A thumb-nut Y holds the scraper tight and the block on the arm.

In addition to the plane and scraper above described a sandpaper-block is furnished, which consists of upper and lower blocks U U'. The lower block is faced on its lower side with a rubber pad Z to cushion it in its work, and on its upper face project brad-points u, on which the paper is pressed to hold it in place while the upper block U is put in position. This upper block U has an opening in its middle to receive a perforated stud W, which is mounted on the top of the lower block and which by means of a key V acts to force the upper block down upon it. The key V has a cam-shaped projection v', which is greater in breadth than in height, and as this is inserted flatwise in the slot w of the stud W and turned edgewise by its lever v² it forces the top block down upon the lower block and clamps the ends of the sandpaper bent thereover. The upper block also carries on its upper face ears Y' and a thumb-screw Y² for attachment to the arms of the machine.

All of these tools are readily removable by thumb-nuts and can be substituted one for another in a few minutes. The machine may also be easily dismantled, so that it can be packed in an ordinary carpenter's chest.

A rubber-faced buffer-rail X (shown in Fig. 1) is thrown out around the machine to prevent its striking and damaging base-boards or walls.

The head H is supported by a swiveled caster Y, which allows the machine to be turned and pushed in any direction, while the spring-pressed arms hold the planes or other tools to the floor with a firm steady pressure.

The number of arms and tools may of

course be increased and the parts variously modified without departing from the spirit of my invention.

What I therefore claim, and desire to secure by Letters Patent, is—

- 5 1. In a floor - planing machine, a rotary head, pivoted arms upon said head carrying tools, and springs for holding said tools in contact with the floor.
- 10 2. In a floor - planing machine having wheels, a rotary head, pivoted arms upon said head carrying tools, springs for holding said tools in contact with the floor and means for rotating the head from said wheels.
- 15 3. In a floor-planing machine mounted upon wheels, a rotary head, means to rotate said head from said wheels, pivoted arms upon said head, tools connected with said arms, springs for holding said tools in contact with

the floor and a swiveled caster for supporting 20 said head.

4. In a floor-planing machine the combination of the rotary head, means to drive said head, arms pivoted thereto, a spring bearing upon said arms and adjusting means for increasing the pressure of the spring thereon. 25

5. In a floor - planing machine, a rotary head, an arm pivoted thereto, said arm carrying a plane having the forward end of its face rounded up, and springs for holding 30 said plane in contact with the floor.

In testimony whereof I affix my signature in presence of two witnesses.

FRANK HERBECK.
